(57) **CLAIM**

The ornamental design for a foot-operated switch, as shown and described.

DESCRIPTION

FIG. 1 is a top plan view of a first embodiment of the foot-operated switch in accordance with our new design;

FIG. 2 is a front perspective view thereof;

FIG. 3 is a rear elevation view thereof;

FIG. 4 is a left elevation view thereof, the right elevation view being a mirror image;

FIG. 5 is a bottom plan view thereof;

FIG. 6 is a front elevation view thereof;

FIG. 7 is a top plan view of a second embodiment of the foot-operated switch in accordance with our new design;

FIG. 8 is a front perspective view thereof;

FIG. 9 is a rear elevation view thereof;

FIG. 10 is a left elevation view thereof, the right elevation view being a mirror image;

FIG. 11 is a bottom plan view thereof; and,

FIG. 12 is a front elevation view thereof.
